UNITED STATES PATENT OFFICE.

ADOLF EWALD GULL, OF LONDON, ENGLAND.

CENTRIFUGAL AND TURBINE PUMP AND THE LIKE.

1,413,911.

Specification of Letters Patent. Patented Apr. 25, 1922.

Application filed May 20, 1920. Serial No. 383,022.

To all whom it may concern:

Be it known that I, ADOLF EWALD GULL, a citizen of the Republic of Switzerland, residing at London, England, have invented new and useful Improvements in Centrifugal and Turbine Pumps and the like, of which the following is a specification.

This invention relates to rotary pumps, such as centrifugal, turbine, and the like pumps, in which a certain static or dynamic head or pressure is obtained by imparting to a part of the fluid to be pumped a certain amount of kinetic energy by means of an internal impeller and transmitting this energy to the whole of the fluid being pumped by means of jets or blades of pressure-fluid issuing from and moving bodily with a ring of rotating nozzles or other suitable apertures connected to or forming part of the discharge chamber of the internal impeller, such jets acting simultaneously as ejectors and as blades imparting tangential velocity to the fluid being pumped.

In order that my invention may be readily understood, I will describe it with reference to the accompanying drawings, which illustrate one way in which my invention may be carried out, and in which,

Figure 1 is a sectional elevation of a pump embodying my invention.

Figure 2 is a cross section on the center line of the discharge branch.

Figure 3 is a section through the internal blading of the rotor, drawn to a larger scale.

Figure 4 is a section through the nozzles of the rotor; and

Figure 5 is a plan view of such a nozzle.

The rotor *a* runs freely in the casing *b* which forms one large chamber, to which and from which lead respectively the suction branch *c* and the discharge branch *d*. This chamber is, however, divided into a number of distinct and well defined chambers or passages by the rotor, which is placed concentrically within the casing. Thus the suction branch *c* leads into a suction chamber *n* which in turn expands to form the annular whirl-chamber *l* into which the jets from the nozzles *i* discharge. Similarly the discharge branch *d* is connected to a discharge chamber *o*, which is a continuation of the annular whirl-chamber referred to above.

The nozzles *i* from which the jets of pressure-fluid are discharged, form part of the rotor, and constitute outlets for the pressure-fluid discharged through the S shaped cham-

ber *h* by the internal impeller shown in section in Fig. 3. The suction of this impeller is in the discharge chamber *o* of the pump, and may be protected by a strainer *m*.

When the pump is working, a part of the fluid to be pumped passes through the rotor, the quantity being determined by the size of the nozzles and the pressure created by the internal impeller. The fluid is drawn from the discharge chamber *o*, and passed through the blading *g* of the internal impeller, which imparts to it, in the form of pressure, the energy transmitted through the shaft *e*.

After passing through the S shaped chamber the fluid reaches the nozzles, where its potential energy is transformed into kinetic energy in the form of jets issuing from the revolving rotor at a high speed and entering the chamber *i*.

It is a well known fact that a jet of fluid, issuing at a high speed from an orifice, partakes of the characteristics of a solid body, in so far as it possesses great rigidity. Thus it follows that jets issuing from apertures in a revolving body tend to revolve as a whole with such body. The purpose of my rotor is to create jets of this character. In order to impart to these jets a blade-like form, the apertures of the nozzles are formed as elongated rectangles, as shown in Fig. 5, the longer axis of the rectangle being parallel to the axis of the shaft. These blade-like jets, revolving with the rotor, impart tangential velocity to the fluid in the chamber *l*, and at the same time have an ejecting influence. In doing this the kinetic energy in the jets is imparted to the whole volume of fluid passing through the whirl-chamber. It will be understood that the specific shape of these fluid-blades will in each case be determined by the pressure against which the pump is working, but the power of the jets remains substantially constant, owing to the fact that the suction of the internal impeller stands under the pressure of the discharge chamber.

In operation the rotation of the rotor causes fluid to flow into the interior of the casing through the inlet *C*. This produces a head or pressure on the discharge side of the casing with the result that the portion of fluid being pumped passes through the filters *m*, the whirl passages formed by the internal blades *g*, into the S shaped chamber *h* and is finally projected in the form of blade like jets through the nozzle *i* at high velocity. These jets are carried round with

the rotor and as the same are spaced from each other they form between them separate compartments containing the fluid being pumped. This fluid is discharged onto the 5 internal periphery of the casing in a substantially tangential direction. It is thus caused to pass out through the outlet *d* under a considerable pressure. It will be seen that the velocity of the streams issuing from 10 the nozzles *i* increases with the pressure on the discharge side of the pump so that the tendency of the blade like streams to bend rearwards under the discharge pressure is automatically counterbalanced to a certain 15 extent by the increase in the velocity of their discharge.

What I claim is:—

1. A centrifugal pump comprising a casing having an inlet, and an outlet, an impeller rotatably mounted within said casing, and a plurality of passages within said impeller, each of which has an outlet opening into the inlet side of the casing, whereby part of the fluid being pumped is caused 20 to pass through said passages under the discharge pressure of the pump and be ejected into the inlet side of the casing by the impeller by reason of its rotation, said jets or blades serving to induce fluid through the 25 inlet of the casing and discharge the same through the outlet of the same.
2. A centrifugal pump comprising a casing having an inlet and an outlet therein, an impeller rotatably mounted within said 30 casing, said impeller having a plurality of passages extending therethrough, each passage having an inlet at one end and an outlet at the other end, said inlet being disposed on the discharge or outlet side of the 35 casing whereby part of the fluid being pumped passes through said passages under

the discharge pressure of the pump and is ejected through the outlets of said passages in a radial direction as fluid streams of blade like form. 45

3. A centrifugal pump comprising a casing having an inlet and an outlet therein, a rotor rotatably mounted within said casing, a plurality of passages extending transversely therethrough, each passage being of 50 volute form and communicating with a common annular chamber of **S** form in cross section, inlets effecting communication between said volute passages and the discharge side of the pump casing, outlets effecting 55 communication between the common annular chamber and the inlet side of the pump casing and nozzles in said outlets adapted to impart a jet or blade like form to the issuing fluid. 60

4. A centrifugal pump comprising a casing having an inlet and an outlet opening therein, the internal peripheral surface of the casing expanding gradually from the inlet side to the outlet side of the same, 65 a rotor rotatably mounted concentrically within said casing so as to separate the inlet openings, a plurality of passages extending transversely therethrough, each passage being of volute form and communicating with 70 a common annular chamber of **S** form in cross section, inlets effecting communication between said volute passages and the discharge side of the pump casing, outlets effecting 75 communication between the common annular chamber and the inlet side of the pump casing, and nozzles in said outlets adapted to impart a jet or blade like form to the issuing fluid.

In witness whereof I affix my signature. 80

ADOLF EWALD GULL.
